CLAIM

The ornamental design for a wireless network accessing device, as shown and described.

DESCRIPTION

FIG. 1 is a perspective view of a “wireless network accessing device” showing my design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The portion shown in the broken lines depict environmental subject matter and form no part of the claimed design.
